YARN BALL WINDER

Bernard August Swanson, 11805 SE. 54th Place,
Bellevue, Wash. 98004

Filed Nov. 29, 1968, Ser. No. 14,723

Term of patent 3½ years

Int. Cl. D15—08

U.S. Cl. D47—5

Fig. 1.

Fig. 2.

FIG. 1 is a side elevational view of a yarn ball winder showing my new design, the side opposite being substantially similar thereto; and

FIG. 2 is an isometric view thereof.

I claim:

The ornamental design for a yarn ball winder, as shown and described.
